UNITED STATES PATENT OFFICE.

HERMAN G. TENHOLDER, OF BEAUMONT, TEXAS, ASSIGNOR OF ONE-HALF TO GEORGE W. SMYTH LUMBER COMPANY, OF BEAUMONT, TEXAS, A CORPORATION OF TEXAS.

FORM-HOLDER AND WALL-TIE.

1,255,811.

Specification of Letters Patent.

Patented Feb. 5, 1918.

Application filed November 7, 1917. Serial No. 200,803.

To all whom it may concern:

Be it known that I, HERMAN G. TENHOLDER, citizen of the United States, residing at Beaumont, in the county of Jefferson 5 and State of Texas, have invented certain new and useful Improvements in Form-Holders and Wall-Ties; and I do hereby declare the following to be a full, clear, and exact description of the invention, such as 10 will enable others skilled in the art to which it appertains to make and use the same.

This invention relates to building constructions and particularly to a form holder and wall tie for use in the construction of 15 concrete or other plastic formed structures in which temporary molds or forms are employed to receive the plastic material which is subsequently permitted to set and harden to form the desired finished wall or 20 cast, and relates particularly to a form holder and wall tie as disclosed in my Letters Patent May 1, 1917, Number 1,224,810.

The form of the tie holder illustrated in the above mentioned Letters Patent is provided on one of its sides with a plurality 25 of notches each of a width substantially equal to the thickness of the mold section there being a pair of the notches adjacent the ends of the bar of tie and also a central 30 pair of spaced notches which were formed between central downwardly projecting portions forming walls of the central notches. It is one of the objects of the present invention to improve this tie and form holder 35 by eliminating the central projecting portion and forming a single slot with uninterruptedly facing side walls against which the inner mold members are adapted to be wedged and held in position as determined 40 by the spacing of the shoulders by the central single slot.

It is a further object of the invention to 45 reduce the weight of the form holder and wall tie to therefore lessen the cost of construction of the same. It is also an object of the present invention to provide such a form holder and wall tie as will enable it to be assembled with more facility in the erec-

tion of the form and which will be more convenient to handle for the reason that the 50 single central space enables emplacement of the tie or form holder over the upper edges of the inner form sections with greater facility and ease of operation than is possible, when the bars are formed with two 55 central notches which has each a width substantially equal to the thickness of the mold section.

A further object of the present invention is to provide for the secure wedging of the 60 mold-sections in position against the opposed faces at the ends of the central slot and to that end I provide a wedging means of suitable construction whereby the sections are firmly and immovably held against 65 their respective seats or shoulders at the sides of the central slot.

With the above objects in view and others which will be readily manifest in the following specification and which will be clear 70 to those skilled in the art, the present invention consists of a rigid and preferably unitary form holder and wall tie as more fully hereinafter described and illustrated in the accompanying drawings and particularly set forth in the appended claims, in 75 which drawings:

Figure 1 is a perspective view of a wall in the course of construction, showing the form holders in position to retain the form 80 sections in place.

Fig. 2 is a side elevation of one of the ties.

Fig. 3 is a bottom plan view of the same, and

Fig. 4 is a plan view of a portion of a mold showing the tie in position and illustrating the wedges in position to secure the mold sections in place.

It will be understood that my present 90 invention provides for the erection of a suitable concrete mold or form as illustrated in Fig. 1, which may comprise outer section 2 of any suitable dimensions which define the outer surface of the wall 3 for instance 95 and also provides for the holding in posi-

tion the inner mold sections 10-10 when a hollow wall as here shown is to be erected it being understood of course that the tie 5 may be utilized to hold the outer section 2 to form a solid wall in which case the inner mold sections 10-10 may be omitted.

The tie contemplated in this invention consists of a substantially flat rectangular bar 5 having adjacent its ends on one side, 10 seats 6 of a width approximating the thickness of the outer mold section 2 for instance so that when the bar is applied to the top edges of the sections as shown in Fig. 1 the latter will be engaged by the seats 6-6 and held against inward or outer movement. 15 The inner sides of the seats 6 are formed by downwardly projecting shoulders 7 the faces 8-8 of the seat being formed being the shoulder 7 and heads 9 having faces 20 which project above and below the upper and lower side faces of the bar 5, the upwardly projecting faces of the heads 9 forming rests against which the lower edges of the superposed sections 2 are supported. 25 As set forth in the patent above mentioned for the purpose of severing the ends of the bar 5 after the concrete wall has hardened, the side edges of the bar 5 are inwardly notched as at 12 to form weakened necks 30 which are narrowest in the transverse plane of the inner surfaces 8 formed by the shoulders 7 so that the heads 9 when broken off by a blow from a hammer will break along the line at 11 which is flush with the outer 35 surface of the concrete wall.

The present invention more particularly consists in the provision of a single, central, elongated, slot or recess 6' having uninterruptedly opposing side surfaces 8' forming 40 respective seats for the adjacent inner or central mold sections 10-10 utilized to form a hollow wall.

In this form of invention the tie 5 is applied to the upper edges of a plurality of mold-sections in the erection of a concrete wall and the inner mold-sections are held firmly against the seat edges 8' by any suitable wedging means which may be introduced between the inner sections 10-10 to 45 force the sections firmly and positively in place against the sides of the central slot 6' and will hold them into proper position and spaced relations. One form of wedging means is illustrated herein as comprising a 50 pair of wedge blocks for each tie 5 the blocks 15 being of suitable width and length and angular form as illustrated in Fig. 4, one of the blocks being adapted to be nailed to one of the inner mold sections as at 16 55 while the other block at 15' is adapted to be driven firmly in between the incline surface of one block at 15 and the adjacent surface of the inner mold section to force these sections into position against the side faces of 60 the seat 6'.

After the form has hardened in the mold the removable wedge or wedges or blocks 15' may be driven out and the sections knocked down and removed for use in other positions in the construction leaving the wall 70 tie 5 embedded in position the heads of which ties are adapted to be removed at any time during the erection of the building by a blow from a hammer or other convenient tool to leave the ends flush to the surface 75 of the wall.

It is understood of course that the proportions and dimensions of the form holders and their respective wedges may be varied according to the dimensions of the construction being erected and that the ties may be made of any suitable material and in any suitable manner, although I have found that they may be cast at a comparatively low cost. 85

What is claimed is:

1. A concrete form holder and wall tie consisting of a bar having on one side, near each end, projecting shoulders having outwardly facing seats and on the same side 90 projections having spaced, directly facing shoulders to receive a pair of inner mold-sections adapted to be secured by lateral pressure upon the seats and adjustable means for securing the inner sections against their 95 seats.

2. A concrete form holder and wall tie consisting of a bar having on one side, near each end, projecting shoulders having outwardly facing seats and on the same side 100 projections having spaced inwardly and directly facing shoulders for a pair of inner mold-sections adapted to be secured by lateral pressure upon the seats, and adjustable fastening means insertible between the said 105 inner sections to hold the same in proper position and apart against said shoulders.

3. A concrete form holder and wall tie consisting of a bar having on one side, near each end, a pair of facing seats to receive 110 each a mold member and on the same side a pair of spaced facing shoulders for a pair of inner mold-sections adapted to be secured by lateral pressure upon the respective seats, the ends of the bar having severable 115 heads with bases projecting from opposite sides of the bar and forming seats and adjustable means for securing the inner sections against their seats.

4. A concrete form holder and wall tie 120 consisting of a bar having on one side, near each end, projecting shoulders forming seats to receive each a mold member and on the same side an elongated seat formed between a pair of opposite shoulders for a pair of 125 inner mold-sections adapted to be secured by lateral pressure upon the seats, and adjustable means insertible between the said sections to hold the same in proper position and apart. 130

5. A mold and wall tie consisting of a relatively flat body having one face provided near each end with a narrow slot to substantially fit the edge of a mold section, 5 and provided between said slots with a wider slot to receive a pair of adjacent inner

mold sections adapted to be wedged at their top edges against the opposed sides of the central slot and adjustable means for securing the inner sections against their seats. 10

In testimony whereof I affix my signature.
HERMAN G. TENHOLDER.
